UNITED STATES PATENT OFFICE.

THOMAS EDMUND HOLMES, OF NETHER EDGE, SHEFFIELD, ENGLAND, ASSIGNOR TO THE UNITED ENGINEERING & FOUNDRY COMPANY, OF PITTSBURGH, PENNSYLVANIA, A CORPORATION OF PENNSYLVANIA.

COMBINED STEAM-HAMMER AND FORGING-PRESS.

1,275,688.

Specification of Letters Patent. Patented Aug. 13, 1918.

Application filed February 14, 1914, Serial No. 818,750. Renewed April 18, 1918. Serial No. 229,417.

To all whom it may concern:

Be it known that I, THOMAS EDMUND HOLMES, a subject of the King of England, and resident of Nether Edge, in the city of 5 Sheffield, England, have invented a new and useful Improvement in Combined Steam-Hammers and Forging-Presses; and I do hereby declare the following to be a full, clear, and exact description thereof.

10 My invention relates to a combined steam-hammer and forging-press.

The object of my invention is to provide a machine adapted for forging metal on the principle set forth in my United States Letters Patent No. 813,209, in which the forging is accomplished by the employment of a steam-intensifier, and at the same time a machine which may be quickly transformed into a steam-hammer by means of which 20 blows may be administered to the metal in quick succession in the manner characteristic of such steam-hammers.

To these ends, my invention comprises the novel features hereinafter set forth and 25 claimed.

In the accompanying drawings, Figure 1 is a vertical elevation of my improved machine; Fig. 2 is a vertical section of the hammer or forging-press proper; and Fig. 3 is 30 a sectional view of valve controlling the supply of motive fluid to the lifting cylinder.

In the drawing, the numeral 2 designates a suitable cast-steel frame which carries the hydraulic pressure-cylinder 3 within which 35 operates the ram 4. The ram 4 is forced downward by fluid pressure introduced by means of the pipe 5. The smaller diameter of the ram 4 extends up through the hydraulic pressure cylinder 3, a suitable stuffing 40 box being provided in said cylinder. The fluid pressure employed, may be derived from a pump accumulator system, or from a steam-intensifier system, such as illustrated and described in my prior United States Patents 45 Nos. 813,209 and 898,365. In the present case I have illustrated in Fig. 1 of the drawings, a steam-intensifier system for supplying fluid-pressure to the pipe 5, and this intensifier system is the same, or substantially the same, as that illustrated in my prior Patent No. 898,365, and I do not deem 50 it necessary to refer to and describe in detail the parts included in said steam-intensifier system, other than that the steam-cylinder 6 has a piston therein, which is connected up to

the ram 7, which works in the cylinder 8. The admission and exhaust of steam in cylinder 6 is controlled by suitable valves connected up by links and levers to the operating lever 9, the movement of the piston in the 60 steam-cylinder 6 of the intensifier, being automatically controlled in such manner that the movement of said piston in performing its working stroke, will cause the supply of steam to be cut off in accordance with the 65 position to which the hand-lever has been set, all as clearly set forth and illustrated in my said prior patents.

The tool-holder 10 is contained within the bushing 11 in the frame 2 and said tool-holder carries the upper-die 12, which operates upon the work carried by the lower-die 13.

The lifting-cylinder 14 is carried above the cylinder 3 by means of the columns 15, supported by the frame 2. Within the lifting-cylinder 14 is the piston 16, to which is attached the piston-rod 17. This piston rod 17 extends down through a bored hole in the ram 4, and is rigidly keyed to the tool-holder 10, as illustrated in Fig. 2. The pipe 18 connects with the upper end of the lifting-cylinder 14 to admit air or steam to a point above the piston 16, for lowering said piston, and a pipe 19 is connected with the 85 lower end of said lifting-cylinder 14 for admitting the motive fluid for raising the piston 16. The pipes 18 and 19 are connected up to the four-way valve 20 illustrated in detail in Fig. 3. The piston-valve 21 controls the ports leading to the pipes 18 and 19 and also brings said pipes into connection with the exhaust-pipe 22. The steam or other motive-fluid for operating the lifting-cylinder 14 is supplied by the pipe 23, which 90 is connected up to the 4-way valve 20 and in order to throttle or shut off the supply of steam or other fluid from the pipe 23, a plug-valve 24 is provided, which is operated by the hand lever 25.

The pipe 23 is connected up with a suitable 95 3-way valve 26. This valve 26 is connected up with the motive-fluid supply and may be operated by the lever 9 in a manner similar to the way of operating a like valve in my 105 said prior Patent No. 898,365.

The piston-valve 21 has the rod or stem 27 connected thereto, passing through the guide 28. Pivoted to the lower end of the stem 27 is the swinging-sleeve 29. A lever 110

30 is pivotally connected to the tool-holder 10 and said lever is in sliding engagement with the sleeve 29. A link 31 is connected with sleeve 29 and short arm 32 of the lever 33.

A key 40 passes through an opening in the frame 2 and said key engaged with its inner end 41 the collar 42 on the ram 4 and retains said ram in its elevated position when the 10 machine is employed as a steam-hammer. To release said ram it is only necessary to turn the key 40 to disengage the end 41 from the collar 42.

When the machine is being used as a forging press, operating on the steam-intensifier system, the 4-way valve 20 is so set that the lower end of the lifting cylinder 14 is connected with the supply pipe 23 and the upper end of said cylinder is open to the exhaust, 15 said valve remaining stationary during the time that the machine is being used as a forging-press. The key 40 is released from the collar 42 of the ram 4. By moving the hand-lever 9, the steam is admitted to the 20 steam-cylinder 6 of the intensifier and the high pressure water is admitted to the system through the pipe 5, and acts to lower the ram 4, together with the tool, to perform the forging operation. The valve 26 provides 25 a cushion of live steam in the cylinder 14, which gives speed of operation, and lifts the upper tool after each downward movement of the press. During this forging operation, the lever 30 has no effect on the 30 valve 20 when the lever 33 is in neutral position, as indicated in Fig. 1.

When, however, the machine is to be used as a hammer, the lever 9 is placed in neutral position and secured by means of a pin or 40 other device. The key is turned to lock the ram 4 in its elevated position. The valve 26 is set to connect the supply-pipe 23 with the air or steam-supply. Assuming that the 45 press-head 10 and the piston 16 are at the top of their stroke and the valve 20 is in such position that steam or air is admitted to the lower end of cylinder 14, to hold said press-head and piston in this position, the hand-lever 33 is forced down, which will operate 50 the piston-valve 21 so as to admit steam to the upper end of cylinder 14 through the pipe 18, while the pipe 19 is open to the exhaust 22. This will cause the piston 16, together with the piston-rod 17, 55 and tool-holder 10 to descend upon the work supported on the lower-die 13, in such a manner as to strike a hammer blow upon the work, as distinguished from the pressing action of the upper die when the machine 60 is used as a forging-press. As the tool-holder 10 descends, the pivoted end of the lever 30 will be carried along and if the hand-lever 33 is held stationary in the posi-

tion to which it has been moved, it will be observed that the piston-valve 21 will be 65 reversed through the action of the link 31, so as to admit steam to the lower end of the cylinder 14, so forming a steam cushion, and at the same time again raising the tool-holder 10, preparatory to striking another 70 blow. The machine will continue to operate in this manner automatically as a steam-hammer, until the lever 33 is again drawn back to neutral position.

By my invention, I provide a machine 75 that combines the forging-press and steam-hammer in a compact simple form, by means of which I am enabled to secure all of the advantages of the forging-press operating under the steam-intensifier system, together 80 with all of the advantages which go with such a forging press in certain lines of work, and at the same time am enabled to transform the machine quickly into a steam-hammer, where, for certain kinds of work, the 85 steam-hammer may be found desirable.

What I claim is:

1. A machine of the character described, comprising a suitable frame, a lower die, a tool-holder, a cylinder, a ram in said cylinder above and in line with said tool-holder said ram having a reduced portion extending out of and above said cylinder, a cylinder above and in line with said first-named cylinder, a piston in said last-named cylinder, a piston rod extending down through said ram, connections between said piston rod and said tool-holder, and a releasable support for said ram for holding same in its elevated position, means for supplying motive fluid alternately to opposite ends of said second-named cylinder whereby said tool-holder may be raised and lowered independently of said ram; 90

2. In a machine of the character described, comprising a suitable frame, a lower die, a tool-holder, a cylinder, a ram in said cylinder in line with said tool-holder, said ram having a reduced portion extending through the upper end of said cylinder, means for supplying fluid pressure to said cylinder, a lifting cylinder, a piston therein, a piston rod connected to said piston passing down through said ram and connected to said tool-holder, means for supplying motive fluid alternately to opposite ends of said lifting cylinder, and a key in said frame adapted to engage said ram in its elevated position whereby said tool-holder may be moved up and down independently of said ram. 110

In testimony whereof, I the said THOMAS EDMUND HOLMES have hereunto set my hand.

THOMAS EDMUND HOLMES.
